(57) **CLAIM**

The ornamental design for a closure for a container, as shown and described.

DESCRIPTION

FIG. 1 is an isometric view taken from the top front and right side of my new design of a closure for a container, and FIG. 1 shows the closure with the lid closed after initial actuation to expose tamper evident tabs on the lid of the closure; FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

In the drawings, the broken lines show portions of a closure for a container that form no part of the claim.
